225,901

WATERPROOF PHOTOGRAPHIC CAMERA

Ohiko Yagi, Yokohama, Japan, assignor to Kabushiki
Kaisha Ricoh, Tokyo, Japan

Filed July 14, 1971, Ser. No. 162,403

Term of patent 14 years

Int. Cl. D16—01

U.S. Cl. D61—1

FIG. 1

FIG. 2

FIG. 3

FIG. 4

FIG. 5

FIG. 6

FIG. 7

FIG. 8

FIG. 1 is a front, top and left side perspective view of a waterproof photographic camera showing my new design; and

FIG. 2 is a front elevational view thereof; and

FIG. 3 is a rear, top and right side perspective view thereof; and

FIG. 4 is a top plan view thereof; and

FIG. 5 is a left side elevational view thereof; and

FIG. 6 is a rear elevational view thereof; and

FIG. 7 is a right side elevational view thereof; and

FIG. 8 is a bottom plan view thereof.

Portions of figures are diagonally lined to indicate transparency.

I claim:

The ornamental design for a waterproof photographic camera, substantially as shown and described.
